(57) **CLAIM**

The ornamental design for an insulated dual thermos, as shown and described.

DESCRIPTION

FIG. 1 is a perspective view of an insulated dual thermos. FIG. 2 is a front elevational view thereof, the rear elevational view being a mirror image of the front view.

FIG. 3 is a top plan view thereof.

FIG. 4 is a bottom plan view thereof; and,

FIG. 5 is a left side elevational view thereof, the right side elevational view being a mirror image of the left side view.
